EDUCATIONAL GAME BOARD

Walter Hesener, 66 Rue de la Prulay, 1217 Meyrin,
Geneva, Switzerland

Filed July 6, 1972, Ser. No. 269,427

Claims priority, application Switzerland Jan. 17, 1972

Term of patent 14 years

Int. Cl. D21—01

U.S. Cl. D34—5 SS

FIG. 1

FIG. 2

FIG. 3

FIG. 4

FIG. 5

FIG. 1 is a perspective view of an educational game board, showing my new design from the front, one side and above;

FIG. 2 is an underplan thereof;

FIG. 3 is a plan view thereof;

FIG. 4 is a rear elevation thereof;

FIG. 5 is an elevation of the side opposite to that visible in FIG. 1.

I claim:

The ornamental design for an educational game board, substantially as shown and described.
